UNITED STATES PATENT OFFICE.

HENRY E. KONDOLF, OF NEW YORK, N. Y., ASSIGNOR TO THE LOX SEAL CORPORATION,
OF BROOKLYN, NEW YORK, A CORPORATION OF NEW YORK.

TAG.

Application filed July 2, 1926. Serial No. 120,022.

My present invention relates generally to tags or tickets, and has particular reference to that type of tag which is designed primarily for inseparable association with a 5 garment or other article of merchandise.

Where articles of merchandise, such as garments, are manufactured of well-known or widely advertised material, it is desirable to insure both the retailer and the ultimate 10 consumer against fraud by substitution of materials. With this object in view, manufacturers of material may supply the manufacturers or vendors of the retail articles with tickets or tags having a small sample 15 or swatch of the material fixedly and inseparably associated therewith, the ticket bearing a guarantee. This ticket is associated or attached to the finished article, such as a garment, and the retailer, as well as the 20 purchaser, may then examine the material of the garment and the material of the sample to make sure that they are identical. The ticket generally bears some such indicia as this: "See that the sample attached to this 25 ticket matches the fabric in the garment. This is your guarantee that this garment is made of genuine such and such material."

It is an object of the present invention to provide a tag of this general character, and 30 more particularly, it is an object of the invention to provide a tag having features of construction which permit its inseparable association with an article of merchandise, and which at the same time permit the inseparable 35 association with the tag of a swatch of the character mentioned.

One of the evils which retailers are often confronted with is the problem of having 40 customers inter-change the tickets or tags on the merchandise which they are inspecting, for the purpose of deceiving the retailer, defrauding him in some way, or returning an article of merchandise after it has been subjected to use.

It is an object of the present invention to 45 provide the tag in a form which permits it to be associated with an article of merchandise in a manner whereby the tag will be inseparable from the article except by mutilating either the article or the tag. More 50 particularly, my present invention has for its object the provision of a tag having the general characteristics of the device dis-

closed in the patent to Behrman, #1,359,951, 55 issued November 23, 1920.

In a tag of the general character described in the last mentioned patent, I have found it satisfactory to utilize a single blank of relatively heavy paper or cardboard, and to double the blank upon itself so as to form superposed layers, the blank being so constructed and folded as to provide a pocket between the layers within which a string or tie of suitable construction may find engagement. The association of the tie is preferably effected by providing an elongated tip or locking pin upon the string, which tip may be inserted through an opening giving access to the interior of the pocket, and said tip being of a character to alter its position after its insertion so as to prevent withdrawal thereof. In a construction of this character, it is essential to render the pocket totally inaccessible (without mutilation of the entire tag) except through some such opening as that just referred to. With this object in view, it is necessary to attach the superposed layers to each other in some inseparable manner whereby the desired inaccessibility of the pocket is produced. 70 75 80

It is an object of the present invention to provide a tag having these general characteristics, and wherein the superposed layers are so associated as to achieve an additional function relating to the engagement of the 85 swatch.

It is a feature of the invention to cement the superposed layers together in such a manner that a portion of the swatch will at the same time be cemented therebetween. 90 It is another feature of the invention to associate the swatch with the layers in such a manner that the swatch is firmly retained along a continuous area; and it is another feature to provide an arrangement wherein a backing is provided for the unattached body portion of the swatch, these features, and others, achieving numerous advantages which will be pointed out more fully hereinafter. 95

It is another object of the invention to provide a tag of the character referred to, wherein a portion thereof is readily removable or detachable without impairing the balance of the tag, thereby permitting such 105 a portion to be utilized as a removable stub

for purposes of record. Accordingly, it is a feature of the invention to associate the superposed layers in such a manner that portions thereof will remain mutually unattached. More particularly, in cementing the layers together, they are adhesively associated along only a predetermined medial area, thereby providing end tabs or stubs which may be readily detached.

10 It is another feature of my invention to provide these unattached end tabs or stubs in a manner whereby they achieve the additional function of normally concealing and protecting the body portion of the swatch. 15 One of the advantages which I gain by providing such unattached tabs, lies in the fact that the lifting of the one or the other of these tabs will render visible either the swatch or any other printed material or indication which is normally covered over and concealed.

Another feature of the invention relates to the provision in at least one of these tabs, or in any other suitable portion of the layers, 25 of a cut-out portion defining or outlining a distinctive mark such as a trade-mark. In a preferred embodiment, one of the end tabs is cut out in this manner, thereby permitting a portion of the swatch to accentuate the 30 trade-mark which is outlined by virtue of the contrasting appearances between the material of the swatch and the material of the tag.

Another object of my invention relates to 35 the string or tie which is utilized in connection with tags of this general character, and consists in providing a binding tie or tie element of a character which obviates the necessity for providing a preformed opening in 40 the inaccessible pocket hereinbefore referred to. The advantages to be gained by an arrangement of this character will be obvious when it is considered that all sorts of attempts are made by defrauding persons to 45 effect the removal of the tag. In connection with this phase of the invention, I achieve an additional advantage with relation to the tag considered as a swatch holder. A feature of the invention lies in providing a tip 50 upon the tie element which is of a character to permit the piercing thereof through unperforated material. More particularly, I provide a tip having an attenuated or pointed end, and I am thereby enabled (1) to 55 render the tag as a whole particularly efficient because of the absence of any preformed or eyeleted opening in the pocket, and (2) to render the association of the swatch doubly secure by making it possible to pass the 60 tie or string right through the swatch itself and the sandwiching layers of material.

In a preferred embodiment, the pointed tip is constructed of a trapezoidal flat blank which may be rolled upon the end of the 65 string or tie.

For the attainment of the foregoing objects and such other objects as may hereinafter appear or be pointed out, I have illustrated embodiments of my invention in the accompanying drawings in which

70 Fig. 1 is a plan view of a blank which may be employed for the provision of the superposed layers;

Fig. 2 is a front view of a completed tag, 75 with a portion broken away to disclose parts which will be otherwise concealed;

Fig. 3 is an enlarged cross-sectional view taken along the line 3—3 of Fig. 2;

Fig. 4 is a rear view of the tag shown in Fig. 2, showing in this figure how the tag 80 may be associated with a garment having button-holes;

Fig. 5 is a diagrammatic representation of the blank which I prefer to employ for the provision of the tie tip, showing the end 85 of the string or tie suitably positioned with respect thereto;

Fig. 6 is a similar view showing the tip rolled about the end of the string;

Fig. 7 is a cross-sectional view taken along 90 the line 7—7 of Fig. 6; and

Fig. 8 is a view substantially like Fig. 2, 95 showing a possible means of utilizing the advantageous features of the tip shown in Fig. 6.

Referring to the drawings, it will be observed that I prefer to employ a substantially rectangular blank 10, this blank being made of relatively stiff paper, cardboard, or other suitable material. The blank is doubled upon itself along a transverse medial line indicated by the dot and dash line 11, and for the purpose of properly providing an inaccessible pocket, the fold is made to occur along the lines indicated in Fig. 1, i. e., along the adjacent lines 12 centrally disposed with respect to the general line of fold 11. After the blank 10 has been doubled upon itself, there will have been provided two superposed layers which I shall term an under-layer 13, and an over-layer 14. Adjacent to the end of one of these layers I provide a transverse line of perforations 15, or in place of such perforations I may suitably treat the layer so as to provide a detachable stub or tab 16. Before the blank 10 is folded upon itself it is coated with adhesive material, such as cement or glue, and in accordance with the present invention, this material is applied along a predetermined medial area which is defined by the line 15, a line 17 symmetrically disposed with respect to the line 15, and the edges of the entire blank. For the purpose of permitting the pocket to be provided, the adhesive material is made to extend only to a substantially elliptical boundary 18 which includes the central portion of the blank.

The blank is now suitably printed, and is doubled upon itself so as to provide a fin- 130

ished ticket as shown in Fig. 2. It will be observed that the top layer 14 is clearly shown in this figure, and that it may be provided with indicia or printing of any desired character. I have shown the stub 16 bearing substantially the same indications, so that the detached stub may be used for record purposes. By virtue of the fold along the lines 12, a pocket 18 has been provided adjacent to the doubled-over end of the ticket, and into this pocket I prefer to insert one end of the binding string or tie 19.

In Fig. 3 I have shown the completed tag, together with the sample or swatch as I prefer to associate it. Referring to both Fig. 3 and Fig. 2, it will be observed that I have provided the swatch in the form of a strip 20 which is substantially co-extensive in width with the width of the tag, and which is slightly longer than the tab 16. In other words, I have shown a binding portion 21 which extends upwardly into the adhesive area, and a main or body portion which is totally disposed between the mutually unattached end tabs of which the tab 16 is illustrative. In Fig. 3, the adhesive material 22 is clearly shown as extending no further than the perforations 15, and it will also be observed how the binding portion 21 of the swatch is securely retained in sandwiched position between the superposed layers 13 and 14.

By virtue of the fact that the adhesive area is continuous, particularly with respect to the outer limits thereof (i. e., along the line 15), the swatch will be held in a manner which is peculiarly secure and efficient. In other words, the binding portion 21 of the swatch is securely held along its entire area; and this renders it particularly difficult to remove the swatch, and it also permits the swatch to assume a neat and uncrinkled position.

The neat disposition of the swatch is rendered further effective by the provision of the rear unattached portion 23 corresponding to the front tab 16. The portion 23 constitutes a backing upon which the swatch may rest and find support, and it will now be obvious that the main portion of the swatch will be neatly and securely held in position between the tab 16 and the portion 23; and that whereas the swatch is normally concealed and protected, manipulation of either the tab 16 or the portion 23 may disclose the swatch to the best advantage.

Referring now to Fig. 4, it will be observed that I have utilized the provision of a rear unattached portion 23 for the additional purpose of displaying a distinctive mark such as a trade-mark. For illustrative purposes, I have shown the portion 23 provided with a cut-out portion 24 defining a star. A portion 25 of the swatch will be visible through this opening, and will ac-

centuate and define the outlines of the opening or mark by virtue of its differing and contrasting appearance.

It will thus be observed that the swatch is securely and practically inseparably associated with the body of the tag, and although I shall presently describe a preferred method of increasing the security with which the swatch is held, and a preferred method of associating a tag with a garment, nevertheless as to certain phases of my invention, the features presently to be described do not constitute limitations.

In Fig. 5 I have shown a blank 26, which may be made of sheet metal or other suitable material, and it will be observed that the blank is substantially trapezoidal in shape, having opposite parallel edges 27, a substantially perpendicular end edge 28, and an oblique edge 29. In the construction of this type of tip, the string or tie 19 has the blank 26 rolled about its end in such a manner that the finished tip will be attached to the string medially of the ends of the tip. Thus, if a string end be laid upon the blank 26 as shown in Fig. 5, the blank may be rolled upon this end as shown in Figs. 6 and 7, and by virtue of the oblique edge 29, a rear portion 30 will be provided, and a forward portion 31 will be provided having a pointed end 32. The position which this tip normally assumes with respect to the tie 19 is transversely of the tie, or at least with the pointed end extending toward the body of the tie 19 (see Fig. 2). In the insertion of the tip into either the pocket 18 or elsewhere, the tip 32 is made to enter first, and after the entire tip has passed through the desired material, it will resume its original and normal position and will prevent withdrawal of the tie.

Thus, by virtue of the attenuated end 31, I am enabled to obviate the necessity of providing preformed openings in the material through which the tie is to be threaded. If both ends of the tie 19 are provided with tips of this character, one end may be made to extend into the pocket 18 of the tag shown in Fig. 2 by merely piercing the tip through the top of this pocket. If desired, one end of the tie may be securely positioned within the pocket before the tag is formed thereby making it necessary to provide the tip only upon the free end of the tie.

In Fig. 8 I have shown a construction of this character, and it will be observed that the end 33 of the tie 19 is securely positioned within the pocket 18. In Fig. 8 I have also shown how the pointed tip may be utilized to advantage in connection with the tag considered as a swatch holder. In order to render the swatch doubly secure, the free end of the tie 19 is made to pass right through the swatch and the sandwiching layers. This is effected by piercing the point

32 through the materials at the desired point. In Fig. 8, and also in Fig. 4, I have shown how the tag may be similarly inseparably associated with a garment, the tie 5 being in each case passed through a button-hole or other opening. By virtue of the pointed tip, it will be obvious that the provision of a button-hole is not essential, and for this reason my tag may be employed to 10 great advantage in connection with articles of merchandise having no preformed openings therein.

It will now be obvious that I have provided a tag which is extremely efficient, 15 which will have a wide variety of uses, and which is nevertheless extremely inexpensive from the standpoint of manufacture. Not only may the tag be inseparably associated with a garment or any article of merchandise, whether such article has or has not any preformed openings such as button-holes; but a sample of the material of the garment or article is simultaneously carried by the tag in an inseparable manner, so that the 20 possibility of defrauding, either by way of unauthorized return or by way of substitution of material, is rendered almost impossible. Furthermore, it will be obvious that my invention permits the tag or swatch 25 holder to be utilized as an advertisement of a trade-mark, and as a recording ticket. Furthermore, the swatch or sample is held in an extremely efficient manner, not only from the standpoint of removal thereof, but 30 also from the standpoint of protection thereof.

It will be obvious that many changes in the details herein described and illustrated for the purpose of explaining the nature of 40 my invention may be made by those skilled in the art without departing from the spirit and scope of the invention as expressed in the appended claims. It is therefore intended that these details be interpreted as 45 illustrative, and not in a limiting sense.

Having thus described my invention and illustrated its use, what I claim as new and desire to secure by Letters Patent is—

1. In a tag of the character described, a 50 pair of superposed layers partially united by adhesive, and a swatch having a portion thereof held therebetween by said adhesive and another portion freely disposed between said layers.

55 2. In a tag of the character described, a pair of superposed layers adhesively united along a continuous area, one of said layers being treated for partial detachment along a line defining an edge of said area, and a 60 swatch between said layers and having a portion held by the adhesive along the marginal area adjacent to said edge.

3. In a tag of the character described, superposed layers arranged and constructed 65 to provide a pocket therebetween at one end

thereof, a tie for said tag including means for engaging the tie within said pocket in an inseparable manner, and a swatch between said layers, the latter being mutually attached in a manner which seals said pocket 70 and firmly engages said swatch.

4. In a tag of the character described, superposed layers arranged and constructed to provide a pocket therebetween at one end thereof, a swatch between said layers at the 75 other end, and means for securing said layers together intermediate their ends to seal said pocket and to engage a portion of the swatch.

5. In a tag of the character described, superposed layers arranged and constructed 80 to provide a pocket therebetween at one end thereof, a swatch between said layers at the other end, and adhesive means for securing said layers together along a medial area to seal said pocket, a portion of said swatch 85 extending into said area to securely engage the swatch in position.

6. A tag of the character described comprising a blank doubled over to form superposed layers, said layers being adhesively 90 associated with each other along a pre-determined area to provide an inaccessible pocket adjacent the doubled-over end, and a swatch sandwiched between the layers and having a portion thereof extending into 95 said area for association with said adhesive.

7. A tag of the character described comprising a blank doubled over to form superposed layers, one thereof having perforations to provide a detachable end tab, said 100 layers being adhesively associated with each other along an area extending no further than said perforations to provide an inaccessible pocket adjacent the doubled-over end, and a swatch having a binding portion within 105 said area and a display portion underneath said tab.

8. In a tag of the character described, in combination, a binding tie for association of the tag with an article of merchandise, a 110 swatch of the same material as that of the article of merchandise, and superposed layers of tag material arranged and constructed to simultaneously sandwich between them both a portion of the tie and a portion 115 of the swatch.

9. In a tag of the character described, in combination, a binding tie having a free threading end for association with an article of merchandise, a swatch of the same 120 material as that of the article of merchandise, and superposed layers of tag material arranged and constructed to form a body portion for the tag and to receive between them both the unfree end of the tie and a portion of the swatch.

10. In a tag of the character described, in combination, superposed layers of tag material, means for fixedly attaching said layers together, a binding tie for association of the 125

tag with an article of merchandise, a portion of said tie extending into sandwiched position between the layers and into engagement with said means for securing the tie to the tag, and a swatch of the same material as that of the article of merchandise, said swatch also having a portion which extends into sandwiched position between said layers and into engagement with said means for securing the swatch to the tag.

11. In a tag of the character described, in combination, superposed layers of tag mate-

rial, a binding tie for association of the tag with an article of merchandise, a swatch of the same material as that of the article of merchandise, and means for fixedly attaching said layers together, said means serving at the same time to secure portions of the tie and the swatch respectively to spaced portions of the tag.

In witness whereof, I have signed and sealed this specification.

HENRY E. KONDOLF.
